US00D961169S

(12) **United States Design Patent** (10) Patent No.: **US D961,169 S**
(45) Date of Patent: **** Aug. 16, 2022**

(54) **MANDIBLE SHIELD**

(71) Applicant: **Gentex Corporation**, Simpson, PA (US)

(72) Inventors: **Emily Hancock**, Arlington, MA (US); **Nathan Winters**, Merrimack, NH (US)

(73) Assignee: **GENTEX CORPORATION**, Simpson, PA (US)

(**) Term: **15 Years**

(21) Appl. No.: **29/823,474**

(22) Filed: **Jan. 18, 2022**

Related U.S. Application Data

(63) Continuation of application No. 29/677,242, filed on Jan. 18, 2019, now Pat. No. Des. 944,461.

(57) **CLAIM**

The ornamental design for a mandible shield, as shown and described.

DESCRIPTION

FIG. 1 is a front perspective view of a mandible shield showing our new design;

FIG. 2 is a rear perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.

The broken lines depict portions of the mandible shield that form no part of the claimed design.

1 Claim, 8 Drawing Sheets
